UNITED STATES PATENT OFFICE.

SAMUEL F. RICHARDS, OF PITTSBURGH, PENNSYLVANIA.

THERMOSTATIC DAMPER CONTROL.

Application filed November 22, 1926. Serial No. 149,825.

The invention relates to a damper controlling device for a hot water heater. The device is connected to the riser leading upward from the heater to the radiators, and the water from this riser acting upon a thermostatic device of the disc type moves a lever to which the damper of the heater is connected. The invention has for its objects the provision of an improved device of the character specified wherein, a very direct and positive control of the thermostat from the water of the riser is secured, and more specifically, the provision of a simple and effective means for securing a circulation of water from the riser around the chamber containing the expansible thermostat discs, whereby the device will respond quickly to changes in temperature in the water. One embodiment of the invention is illustrated in the accompanying drawings, wherein:

Figure 1 is a vertical section through the device and the riser to which it is connected. And Fig. 2 is a section on the line II-II of Fig. 1.

Referring to the drawings, 1 is a T in the riser 2 leading upward from the heater to the radiators, and 3 is an upright casing having the cavity or chamber 4 therein. Integral with this is a second casing 5 having the cavities 5 and 6, 6 surrounding the lower end of the chamber 4. The cavity 5 is separated from the two cavities 6, 6 lying thereabove by means of the partitions 7, 7. These partitions merge at their inner end into the plate or flange 8, which projects out into the riser, and curves downwardly, as indicated in Fig. 1.

Lying in the chamber 4 is the plunger 9 and the series of expansible sheet metal discs 10. These discs are well known in the art, consisting of thin sheet metal containing a liquid having a low vaporizing point, such as acetone. The plunger 9 has an upwardly extending stem 11, projecting through the cap 12 and engaging the lever 13, which has suitable connections (not shown) with the damper of the heater. The lever is shown as pivoted between a pair of lugs 14 carried by the cap, and is guided between another pair of lugs 15, also carried by the cap. A plug 16 is provided as a closure for the clean out opening in the side wall of the casing.

In operation, the water in the riser, which is moving upward strikes the flange 8 and

is deflected inwardly through the cavity 5, turning upward, as indicated by the arrow, at the end of such cavity and flowing back to the riser through the cavities 6, 6. Due to this circulation, any changes of temperature in the riser are quickly communicated to the shell of metal constituting the lower end of the chamber 4 and carrying the discs 10, and this shell in turn affects the expansion discs. With rising temperatures, the expansion of the discs moves the lever 12 upward and cause a closure, or partial closure, of the damper, while a reverse result occurs with decreasing temperatures.

The arrangement of the flange 8 projecting into the riser, in conjunction with the arrangement of the cavities 5 and 6, 6 insures a circulation of water past the thermostatic controlling means, and this in turn causes the device to respond promptly to changes in the temperature of the water.

What I claim is:

1. In combination in a temperature controlling device for use with an upright hot water pipe through which a circulation of water is provided, a casing having a tubular connection leading into said pipe, a laterally extending partition in the casing extending through said connection and projecting into the pipe, an upright casing integral with the first casing and having its lower end extending down into said first casing past said partition, expansible thermostatic means and a plunger mounted in said upright casing, and a communication between the outer ends of the cavities in said first casing lying above and below said partition.

2. In combination in a temperature controlling device for use with an upright hot water pipe through which a circulation of water is provided, a casing having a tubular connection leading into said pipe, a laterally extending partition in the casing extending through said connection and projecting into the pipe, an upright casing integral with the first casing and having its lower end extending down into said first casing past said partition, expansible thermostatic means and a plunger mounted in said upright casing, and a communication between the outer ends of the cavities in said first casing lying above and below said partition, the end of said partition which extends into said pipe being turned downwardly.

3. In combination with the vertical riser

of a hot water system, a vertical casing adjacent the side of the riser provided with expansible thermostatic means and a plunger operated thereby, another casing surrounding the lower end of the vertical casing with its bottom and side walls spaced away from the bottom and side walls of the first casing, a tubular connection leading from the side of said other casing into the riser, and a horizontal partition in said other casing, extending at one end through said connection to the riser and at the other end stopping short of the end wall of said other casing so that a communication is left between the cavities above and below said partition.

4. In combination with the vertical riser of a hot water system, a vertical casing adjacent the side of the riser provided with expansible thermostatic means and a plunger

operated thereby, another casing surrounding the lower end of the vertical casing with its bottom and side walls spaced away from the bottom and side walls of the first casing, a tubular connection leading from the side of said other casing into the riser, and a horizontal partition in said other casing, extending at one end through said connection to the riser and at the other end stopping short of the end wall of said other casing, so that a communication is left between the cavities above and below said partition, the said end of the partition which projects into the riser being turned downwardly.

In testimony whereof, I have hereunto subscribed my name this 20th day of November, 1926.

SAMUEL F. RICHARDS.
